[57] CLAIM

The ornamental design for a writing instrument clip, as shown and described.

DESCRIPTION

FIG. 1 is a perspective view of a writing instrument clip showing my new design;
FIG. 2 is a front elevational view thereof;
FIG. 3 is a rear elevational view thereof;
FIG. 4 is a side elevational view, the opposite side being a mirror image thereof;
FIG. 5 is a top plan view thereof; and,
FIG. 6 is a bottom plan view thereof.

The portion shown in broken lines in FIG. 1 is for information only and forms no part of the instant design.
